UNITED STATES PATENT OFFICE.

LEE S. CHADWICK, OF SHAKER HEIGHTS, OHIO, ASSIGNOR TO THE CLEVELAND METAL PRODUCTS COMPANY, OF CLEVELAND, OHIO, A CORPORATION OF OHIO.

LIQUID-FUEL STOVE.

Application filed February 4, 1922. Serial No. 534,041.

To all whom it may concern:

Be it known that I, LEE S. CHADWICK, a citizen of the United States, residing at Shaker Heights village, in the county of Cuyahoga and State of Ohio, have invented a certain new and useful Improvement in Liquid-Fuel Stoves, of which the following is a full, clear, and exact description, reference being had to the accompanying drawings.

This invention relates to improvements in liquid fuel stoves, particularly to the type used for cooking.

In stoves of this class it is usual to support the fuel reservoir to one side or beyond one end of the stove in inverted position and in dispensing relation to a distributor which has communicative connection with the burners. The reservoir or dispensing receptacle may or may not have hinge connection with the distributor. In either event, however, it has to be inverted while being placed in operative position.

In order to utilize the space above the reservoir and increase the effective supporting area of the stove top, and to protect the reservoir from injury or breakage as by the accidental dropping of things on it (for, as is generally known, these reservoirs usually consist of glass receptacles) the stove top heretofore, in some cases, has been extended over the reservoir, while in other cases a shelf has been hinged or removably connected to the end of the stove above the reservoir. In the case of extending the stove top over the reservoir, the extending portion has lacked proper support for the reason that the presence of brackets or other supporting means therefor would interfere with the placement and removal of the reservoir, the presence of the extended stove top alone making the emplacing and removing of the reservoir inconvenient; and in the case of the hinged or removable shell, it required the extra effort of swinging the shelf out of the way or removing it before the reservoir could be removed or inverted.

My present invention aims to provide a shelf extension over the reservoir which is strongly supported when in normal position and which is so connected to the reservoir, or the carrier therefor, as to be inverted with the same, thus affording increased area of

the stove top while in no way interfering with the convenient manipulation of the reservoir.

To this end, my invention may be defined generally as consisting of the combination and arrangement of elements set out in the claims annexed hereto and illustrated in the drawings accompanying and forming a part hereof and wherein Fig. 1 is a partial front elevation, and Fig. 2 an end elevation of a stove embodying my improvements; Fig. 3 is a view similar to Fig. 2 showing, in full lines the shelf and reservoir in inverted position, or in the position which the parts occupy when the reservoir is to be removed from its carrier, and in dotted lines, in intermediate position; Figs. 4, 5 and 6 are sectional details on the respective lines 4—4, 5—5 and 6—6 of Fig. 2; Fig. 7 is a sectional detail on the line 7—7 of Fig. 5; and Fig. 8 is a perspective view of the shelf supporting bracket.

The stove, with its burners and fuel feeding system, is substantially the same as that shown in by former Letters Patent No. 1,209,811, issued December 26, 1916, and it comprises a top 1, and a base 2 immediately above which the burners (not shown) are supported by and in communicative connection with a supply pipe 3. At each end of the stove an end panel 5 extends between the top and base, and at each corner of the structure there is a leg 6, my present design differing from that shown in the aforesaid patent by having legs which extend from the top of the stove to the floor. The supply pipe 3 extends out through one of the end panels and has connection with a distributing receptacle 10 to which is hingedly connected, at 11, a carrier 12 which supports a reservoir or dispensing receptacle 13, the same being, in the present instance as well as in my patent aforesaid, a glass container having a band 14 secured about its upper end to which the ends of a bail 15 are pivotally connected. When the carrier is in inverted position, the bail 15 is engaged within a hook 16 on the carrier, the reservoir dropping within the carrier, when turned upright as shown in full line in Fig. 3, sufficiently to remove the bail from the hook so that the bail may be swung upward and the reservoir lifted thereby. When the car-

rier is in receiving position, a member 18 thereon engages a stop 19 that is supported by the end panel 5.

The mouth of the reservoir or dispensing receptacle is equipped with a valve 20 which, when conditions permit, is closed by a spring 21, but which is unseated when the reservoir is in inverted position by the engagement of its stem 22 with an abutment portion of the 10 distributing receptacle 10. All of this is clearly disclosed in my patent above referred to.

A shelf 25, having a depending peripheral flange 26, is rigidly connected to and spaced 15 above the upper end of the carrier 12 (considering it in its normal position) by members 27; and by means of a handle 28, situated at the rear end of the shelf 25, the shelf and carrier may be conveniently swung 20 from one to the other of the positions shown in full lines to Figs. 2 and 3. As is clear from Figs. 1 and 2, as well as from Figs. 4, 5 and 6, when the parts are in normal position, the top of the shelf is in the plane of 25 the top of the stove and constitutes, in effect, an extension thereof. To more securely retain the shelf in such position against any sagging under the weight of a load imposed thereon, and to properly position it with respect to the stove structure, I employ the 30 parts illustrated in detail in Figs. 4 to 7. A bracket 30 extends from the adjacent end panel of the stove under the rear end of the shelf and has a part 31 which fits up under 35 the shelf between the side portions of its peripheral flange 26 and engages the under side of its top, the part 31 of the bracket being only a trifle less in length than the distance between the sides of the peripheral 40 flange so as to retain the shelf against appreciable lateral displacement. This bracket 30 is, as are practically all other parts of the structure, formed of sheet metal, and to give it rigidity it is flanged at 33 along its lower 45 edge, is beaded at 35, and the portion 31 is comprised of an upwardly extending part of the body portion of the bracket which had its upper edge embraced by the overturned portion 36 of a plate 37 which, at its lower 50 edge, is turned laterally into a horizontal plane and formed into a triangular part 38 that is flanged downwardly at 39 along its free edge, the end of the flange being turned laterally to provide an ear 40. This ear and 55 the flanged end 41 of the body portion of the bracket have apertures through which connecting means 42, as rivets, may be extended for securing the bracket to the end panel.

Adjacent the forward end of the shelf, a 60 supporting and positioning member 45 extends from the end of the stove top. This member has a supporting base 46 that is secured to the inner side of the flange 47 of the stove top 1, the member extending laterally from said base beneath the flange and

under and upwardly inside the peripheral flange of the shelf 25. An ear 48 rises from the member 45 adjacent the flange of the stove top and its side remote therefrom is inclined downwardly and toward the upturned outer end of said member. The ear 48 and the upturned end of said member thus provide a downwardly converging restricted notch into which the flange of the shelf is guided when it is swung to normal 75 position.

Having thus described my invention, what I claim is:

1. In combination with a stove structure of the character set forth and incorporating 80 a liquid fuel distributor situated to one side of the structure and a dispensing receptacle adapted to be supported in operative relation to the distributor, and a shelf carried by the dispensing receptacle and sustained thereby in a given position with respect to the stove top when the dispensing receptacle is in operative position.

2. In combination with a stove structure of the character set forth and incorporating 90 a liquid fuel distributor situated to one side of the structure and a dispensing receptacle movably supported so as to permit the dispensing receptacle to be moved from a receiving position to a position in operative 95 relation to the distributor, and a shelf carried by the dispensing receptacle and sustained thereby in a given position with respect to the stove top when the dispensing receptacle is in operative position.

3. In combination with a stove structure of the character set forth and incorporating 105 a liquid fuel distributor situated to one side of the structure and a dispensing receptacle movably connected thereto so as to permit the dispensing receptacle to be moved from a receiving position to a position in operative relation to the distributor, and a shelf carried by the dispensing receptacle and sustained thereby in a given position with respect to the stove top when the dispensing receptacle is in operative position, the stove 110 structure and shelf having parts cooperating to maintain the shelf in proper relation to the stove top.

4. In combination with a stove structure of the character set forth and incorporating 120 a liquid fuel distributor situated to one side of the structure and a dispensing receptacle movably connected thereto so as to permit the dispensing receptacle to be moved from a receiving position to a position in operative relation to the distributor, and a shelf carried by the dispensing receptacle and sustained thereby in the plane of the stove top when the dispensing receptacle is in 125 operative position, the stove structure and shelf having parts cooperating to maintain the shelf in the plane of and in otherwise proper relation to the stove top.

5. In combination with a stove structure of the character set forth incorporating a liquid fuel distributor situated beyond one end of the structure and a dispensing receptacle movably connected thereto so as to permit the dispensing receptacle to be moved from a receiving position to a position in operative relation to the distributor, a shelf carried by the dispensing receptacle and sustained thereby in a given position with respect to the stove top when the dispensing receptacle is in operative position, and a member carried by the stove structure and interfitting with parts of the shelf to maintain the shelf against lateral displacement with respect to the stove structure. 10
6. In combination with a stove structure of the character set forth incorporating a liquid fuel distributor situated beyond one end of the structure and a dispensing receptacle movably connected thereto so as to permit the dispensing receptacle to be moved from a receiving position to a position in operative relation to the distributor, a shelf carried by the dispensing receptacle and sustained thereby in a given position with respect to the stove top when the dispensing receptacle is in operative position, and a positioning device carried by the stove structure and cooperating with the shelf to properly locate the shelf with respect to the stove top when it is moved with the dispensing receptacle to normal position. 15
7. In combination with a stove structure of the character set forth incorporating a fuel distributor located to one side of the structure and a dispensing receptacle hingedly supported in operative relation to said distributor so that it may be swung from a position at one side thereof to an inverted position thereabove, and a shelf carried by the dispensing receptacle and sustained thereby in given relation to the stove top when the dispensing receptacle is in inverted position. 20
8. In combination with a stove structure of the character set forth incorporating a fuel distributor located beyond the end of the structure and a dispensing receptacle hingedly supported in operative relation to said distributor so that it may be swung from a position at one side thereof to an inverted position thereabove, a shelf carried by the dispensing receptacle and sustained thereby in given relation to the stove top when the dispensing receptacle is in inverted position, and a supporting member projecting from the end of the stove structure and on which the shelf rests when in normal position. 25
9. In combination with a stove structure of the character set forth incorporating a fuel distributor located to one side of the structure and a dispensing receptacle hingedly supported in operative relation to said distributor so that it may be swung from a position at one side thereof to an inverted position thereabove, a shelf carried by the dispensing receptacle and sustained thereby in given relation to the stove top when the dispensing receptacle is in inverted position, said member cooperating with the shelf to retain it against lateral displacement with respect to the stove top. 30
10. In combination with a stove structure of the character set forth incorporating a fuel distributor located to one side of the structure and a dispensing receptacle hingedly supported in operative relation to said distributor so that it may be swung from a position at one side thereof to an inverted position thereabove, a shelf carried by the dispensing receptacle and sustained thereby in given relation to the stove top when the dispensing receptacle is in inverted position, and a positioning device carried by the stove structure and having a downwardly converging notch into which a part of the shelf is engaged when the shelf is swung to normal position thereby to properly position the shelf laterally with respect to the stove top. 35
11. In combination with a stove structure of the character set forth incorporating a fuel distributor located to one side of the structure and a dispensing receptacle hingedly supported in operative relation to said distributor so that it may be swung from a position at one side thereof to an inverted position thereabove, a shelf carried by the dispensing receptacle and sustained thereby in a given relation to the stove top when the dispensing receptacle is in inverted position, the shelf having a depending peripheral flange, and a bracket projecting from the stove structure and having a portion which engages the underside of the shelf and fits between the side portions of the peripheral flange thereof when the shelf is in normal position. 40
12. In combination with a stove structure of the character set forth incorporating a fuel distributor located to one side of the structure and a carrier for dispensing receptacle hingedly supported in operative relation to the distributor so that said carrier may be swung from a position at one side of the distributor to an inverted position thereabove, a shelf supported by the carrier and sustained in a given relation to the stove top when the carrier is in inverted position, and means projecting from the stove structure and cooperating with certain of the swinging parts to maintain the shelf in said given position with respect to the stove top. 45
13. In combination with a stove structure of the character set forth incorporating a liquid fuel distributor situated to one side of the structure and a dispensing re- 50

ceptacle movably connected thereto so as to permit the dispensing receptacle to be moved from a receiving position to a position in operative relation to the distributor, 5 a shelf carried by the dispensing receptacle and sustained thereby in a given position with respect to the stove top when the dispensing receptacle is in operative position, and a handle carried by the shelf 10 by means of which, through the intervention of the shelf, the dispensing receptacle may be moved to and from dispensing position.

14. In combination with a stove structure of the character set forth incorporating 15 a liquid fuel distributor situated to one

side of the structure and a dispensing receptacle hingedly connected thereto so as to permit the dispensing receptacle to be swung from a receiving position at one side 20 of, to an inverted dispensing position above, the distributor, and a shelf carried by the dispensing receptacle and sustained thereby in a given position with respect to the stove top when the dispensing receptacle 25 is in operative position, the shelf serving as means through which the dispensing receptacle may be moved to and from dispensing position.

In testimony whereof, I hereunto affix 30 my signature.

LEE S. CHADWICK.
